UNITED STATES PATENT OFFICE.

ADRIEN GREDELUE, OF NEW YORK, N. Y., ASSIGNOR TO LOUIS BESSIÈRE, OF PARIS, FRANCE.

DESIGN FOR A DRINKING VESSEL.

40,673.

Specification for Design.

Patented May 3, 1910.

Application filed February 4, 1910. Serial No. 542,143. Term of patent 14 years.

To all whom it may concern:

Be it known that I, ADRIEN GREDELUE, a citizen of the Republic of France, residing at New York, in the county and State of New York, have invented a new, original, and ornamental Design for Drinking Vessels, of which the following is a specification, reference being had to the accompanying drawing, forming part thereof.

Figure 1 shows a side elevation of the

drinking vessel showing my new design, and Fig. 2 is an inverted plan view of the bottom of the same.

I claim:

The ornamental design for a drinking vessel, as shown.

ADRIEN GREDELUE.
